BELT SANDER

William Palmer Iggulden, Balcombe Park Lane,
Beaumaris, Victoria, Australia

Filed Feb. 3, 1964, Ser. No. 78,483

Claims priority, application Australia Aug. 16, 1963

Term of patent 14 years

(Cl. D37—1)

FIG. 1 is a front perspective view, taken from above, of a belt sander showing my new design;

FIG. 2 is a rear perspective view thereof, taken from below;

FIG. 3 is a left side elevational view thereof;

FIG. 4 is a front elevational view thereof;

FIG. 5 is a right side elevational view thereof;

FIG. 6 is a rear elevational view thereof; and

FIG. 7 is a top plan view thereof.

I claim:

The ornamental design for a belt sander, as shown.
